UNITED STATES PATENT OFFICE.

PASQUALE LO CASCIO, OF BROOKLYN, NEW YORK.

DESIGN FOR A PERMUTATION-PADLOCK.

53,596.

Specification for Design.

Patented July 15, 1919.

Application filed March 19, 1919. Serial No. 283,682. Term of patent 14 years.

To all whom it may concern:

Be it known that I, PASQUALE LO CASCIO, a subject of the King of Italy, residing at Brooklyn, in the county of Kings and State of New York, have invented a new, original, and ornamental Design for Permutation-Padlocks, of which the following is a specification, reference being had to the accompanying drawing, forming part thereof.

The figure is an elevation of the same showing the permutation padlock and its several combinations, lined and numeraled in ornamentation.

I claim:

The ornamental design for a permutation padlock, as shown.

PASQUALE LO CASCIO.
